(54) **PROPELLING STEAM BOATS, & OTHER
VESELS**

(76) Inventor: **William Scarbrough**

William Starbrough, Savannah, Georgia
S^ollent Patent

The schedule referred to in this S^ollent Patent and making part of the same containing a description in the words of the said William Starbrough himself of his improvement in the construction and Propulsion of Steam or other Boats.

Know all whom these presents shall come, that it has been shewed that Mr. William Starbrough of the City of Savannah in Chatham County State of Georgia have invented new and useful improvements in the Construction and Propulsion of Steam or other Boats & that the following is a full and exact description thereof.

The accelerated Propulsion of the Vessel or Boat as above set forth is to be arrived at first by the diminution of resistance in the water navigated; & secondly, by the increase of the tractive force of the wheels or other means of propulsion through the water. The diminution of resistance is to be done at by the greatest possible reduction of the immovable or draft of water of the Vessel or Boat & by the formation of thin, flat, broad, flat keel which to sustain diminishing as nearly as possible upon the surface. Therefore the bottom of these Vessel Boats at the stern point of bearing should be as nearly as possible flat, without more than one or two of short rise; the greater breadth should be considerably about the one & perhaps most advantageously, within one third of the whole length extending from the stern first. From this point the rise should commence tapering aft; and from far forward should commence tapering to the bow; in both cases gradually in running lines so as to obtain the greatest possible buoyancy or bearing. With the double object of facilitating the steering of the Vessel or Boat and keeping the same as much as possible upon the surface so as to cause the displaced water when escaping from the superincumbent pressure to rise as high as possible on the forward part of the propelling water wheel, and afterwards under the counter stern part the bottom of the Vessel or boat forward should from 15 to 20 feet more or less according to the size of the Vessel Boats about the stern or counter begin gradually to rise or come up from the straight line of the after part so as to attain the height of from 2 to 3 or even more feet, where a perpendicular line would

fall from said stem or bow, water the shaft of the paddle, which should be placed on a right on the abft end of the greater breadth of the Paddle Boat, whereby the displaced water will more readily escape & a very slight yet horizontal inclination of the buckets of the paddle wheel, from a direct right angle from the hull of the boat will not only carry the displaced water under the stern to assist the force of the rudder but will tend to lighten the pressure of the said water on the said buckets, and the wave of the displaced water in the act of revolving, to level must also matter of course urge the boat or vessel forward. Secondly in regard to the increase of the travelling of the water that or other mode of propulsion as no steam or other engine of any considerable length of stroke could keep in advantageous motion wheels of any great diameter with the buckets or paddles now generally in use where any considerable resistance was offered at more than 15 to 20 revolutions in a minute, increased velocity could only be given at the piston engines by the help of gearing the effect of which would be a material encumbrance on the power of the engine and attended with considerable risk of breakage.

The object is then to find a remedy for such inconvenience the difficulties or disadvantages in proportion to the reduction of the diameter of a wheel so well be the diminution of the travel of its periphery during revolution of a diameter that would give but a little over 16 yards whilst the revolution of a 25-foot diameter would cover a distance more than 80 yards, shall the fleet Boat flying on the Hudson Delaware or Chesapeake the diameter of the paddle wheel have been enlarged to the extent the capacity of the Boat and the power of the Engine would admit; one ^{before} we have, to the evidence that Mr. Burrough could only traverse their velocity principally by the augmented diameter of his paddle wheel; he could not have done it on his experimental raft of 75 feet in length. The difficulties & disadvantages which have been suggested in regard to gearing upon the Engine to obtain increased velocity of motion and the enlargement of the diameter of the paddle wheel to augment the travel may however safely and easily be surmounted by shortening the length of the buckets or paddles in a proportionate degree. For example if we place on a wheel 16 feet in diameter arms 9 feet apart in a straight line near the periphery Buckets to be in

lengths and 2 feet in breadth the 16 multiplied into each other would yield a surface of 192 feet square, on a 26 foot wheel with arms at the same distance apart of Buckets only four feet in length were placed they would be 2 in number which multiplied as above would give a surface of 160 square feet. Thus although the reduction in the length of the Bucket was equal to $\frac{1}{3}$ of a foot or $\frac{1}{16}$ the whole surface of immersion in the revolution is reduced only $\frac{1}{16}$ of $\frac{1}{16}$ or $\frac{1}{256}$ whilst there is a clear saving of $\frac{8}{15}$ of a ft. on the surface of the wheel in back water. The saving is not an imaginary advantage we may readily perceive from generally in the large boats of this Country the whole length of the Bucket or paddle, have been divided into two or more parts. We have thus seen that by the formation of the paddles so as to diminish the resistance of the water & by shortening the paddles or Buckets the work or labor of the Engine has been much reduced that much of the risk of breaking in the case of gearing whether by wheels Paddles or otherwise has been superseded. The enormous increase of velocity will not by any means be attained with the soffred loss upon the top or diminution of power which the general rule might lead to indicate for when the impulse or momentum has been once given the augmented speed of the Boat or vessel will more than compensate the Engine for its first expence of power.

As stability or solidity of the construction of the vessel is of primary importance for the correct working of the machinery especially in the case of gearing it is further proposed as the means of attaining it that the paddle wheel because any part of the boat or vessel between or beyond them where the pressure is great should be sustained or supported from the inside of the boat or vessel by the use of projecting iron rods or setting them under the beams or in strong pieces thereunder connecting two or more of them and across the ceiling or sides of the boat or vessel but perpendicularly applied to the same so that the Rock or Blocks acting in the manner of a Key Stone or key stones to the arch, the pressure near the quinault or on the upper part of the Boat or vessel will be transferred to the Rock or Blocks and they in return if necessary will find a reciprocating adequate abutment from the capacity of pressure at the other side on the end of the arch there. But especially of this it is considered that such

rollers or wheels of the largest diameter which can be used, would be advantageously employed in steadying the propelling shafts & partially reducing the friction in their journals.

What I claim as my construction and not previously known in the above described method of constructing propelling shafts in other boats is the peculiar formation of the model of the boat or Yopee as above described and specified in combination with the increased velocity of the propelling wheels to obtain by said combination a more rapid progression of the boat or Yopee as also the application of the inverted cones and friction rollers or wheels, above set forth. It is to be observed that I claim no originality to any of the parts separately.
